Attorney

UNITED STATES PATENT OFFICE.

OWEN F. NELSON, OF DETROIT, MICHIGAN, ASSIGNOR TO COPELAND PRODUCTS INC., OF DETROIT, MICHIGAN, A CORPORATION OF MICHIGAN.

REFRIGERATION.

Application filed January 28, 1926. Serial No. 84,478.

- It is the primary object of my invention to provide a refrigeration brine tank having piping or coils therein so disposed that the cooling effect upon the brine tank will be substantially equally distributed around the ice trays therein, and so proportioned and distributed with reference to the remaining piping or coils in the tank as to freeze water in the trays before cooling the entire tank.
- Another object of my invention is to provide an arrangement of such piping or coils so made that the same constitute a unit which may be fitted in the brine tank after its formation.
- Other and further objects will be apparent as the specification progresses.
- My invention consists in the arrangement, combination and construction of the various parts of my improved device, as described in the specification, claimed in my claims and shown in the accompanying drawing, in which:
- Fig. 1 is a top or plan view illustrating my invention.
- Fig. 2 is an elevation showing the piping or coils utilized in my invention on the line 2—2 of Fig. 3.
- Fig. 3 is an elevation showing my improved arrangement of piping or coils assembled in a refrigeration brine tank.
- I have shown a refrigeration brine tank indicated generally as 5, having an intake fitting 6 and an offtake fitting 7. A continuous piping is arranged in the tank 5 leading from the intake fitting 6 to the offtake fitting 7. As will be seen in Fig. 3, the piping leads downwardly from the intake 6, as at 8, to the bottom of the brine tank, where it is bent, as at 9, and extends across the bottom of the tank, as at 10, is then again bent, as at 11, to again extend across the tank as illustrated by the portion 12; is again bent, as at 13, to provide a portion 15 extending across the tank; is again bent, as at 16, to provide a portion 17 extending across the tank; is again bent, as at 18, to provide a portion 19 extending across the tank, and is again bent, as at 20, to provide a portion 21 extending across the tank. This plurality of bends is best illustrated in Fig. 1 of the drawings, from which it will be seen that the piping has been extended in various return bends to form six transverse extensions across the bottom of the brine tank. The piping is then bent, as at 22, in an upward direction where the same series of bends are effected in the section indicated generally as 23, in Fig. 3 of the drawing. This bending is continued to form layers of piping, between which are four separated spaces 24, 25, 26 and 27 in the coil arrangement to accommodate the ice tray sections 28, 29, 30 and 31 respectively. Each section of the pipe between the various ice tray sections is identical with the other and one description for all of them will suffice. From the top section of this return bent construction, the pipe extends upwardly as at 32 to the top of the refrigerator brine tank, where it is wound in a series of "pan cake" coils, beginning with the large coil 33 to the small coil 34. Such coils are continued from the small coil 34 in enlarged, instead of decreased, diameter to the bottom coil 35, from which the pipe extends upwardly, as at 36, to the outlet 7.
- It will be apparent from the above described arrangement of the pipe or coils that the liquid refrigerant entering the intake fitting will be first passed through the piping around the various ice tray sections in the brine tank, through an arrangement of coils which are not of sufficient length to ordinarily cause boiling of the refrigerant before it has passed the top ice tray section. The result is that the water ice trays in the ice tray sections 28, 29, 30 and 31 will be frozen before the entire brine tank has been cooled to the required point, with the consequent result that the user may have ice promptly instead of being forced to wait until the entire refrigerating element has been cooled sufficiently to freeze water in the ice trays. The arrangement of "pan cake" coils above the ice tray sections adds sufficient length to the piping, through which the refrigerating liquid is passed, to cool the entire brine tank in the ordinary way.
- It will also be apparent that the piping, or coil construction, can be made in a unit, as shown in Fig. 2 of the drawings and may be placed in the brine tank by simply pushing the same therein with the ice tray sections 28, 29, 30 and 31 extending through the spaces 24, 25, 26 and 27.
- It will be obvious that various changes may be made in the arrangement, combination and construction of the various parts of my improved device without departing from the spirit of my invention, and it is

my intention to cover by my claims such changes as may be reasonably included within the scope thereof.

What I claim is:

- 5 1. A refrigerating brine tank having ice tray sections therein, piping in said tank having an intake and outlet connection extending through the tank wall, said piping being extended from the intake to form
- 10 coils directly under and over said tray sections and then to form coils removed from the tray sections.
- 15 2. A refrigerating brine tank having ice tray sections therein, piping in said tank having an intake and outlet connection ex-

tending through the tank wall, said piping being extended from the intake to form return bent coils of single layers of piping directly under and over said tray sections and coils of a plurality of superposed layers of piping removed from the tray sections.

3. A construction as set forth in claim 2 wherein said superposed layers of piping are of varying circumferences.

4. A construction as set forth in claim 2 wherein said piping is formed as a unit with the space between said single layers unobstructed in at least one direction to receive the tray sections.

OWEN F. NELSON.
